Patented Nov. 9, 1976

242,245

WRITING INSTRUMENT

John Nicholas Butler and Stephen Peter Bartlett, London, England, assignors to Alfred Dunhill Limited, London, England

Filed Sept. 9, 1974, Ser. No. 504,659

Term of patent 14 years

Int. Cl. D19—06

U.S. Cl. D19—49

FIG. 1 is a front elevational view of a writing instrument showing our new design with the cap separated from the body portion;

FIG. 2 is a left side elevational view thereof;

FIG. 3 is a rear elevational view thereof;

FIG. 4 is a top plan view of the cap of the instrument;

FIG. 5 is a top plan view of the body of the instrument;

FIG. 6 is a bottom plan view of the cap of the instrument;

FIG. 7 is a bottom plan view of the body of the instrument;

FIG. 8 is an enlarged scale cross-sectional view taken along line 8—8 of FIG. 1; and

FIG. 9 is a left side elevational view showing the cap and body assembled together.

We claim:

The ornamental design for a writing instrument, as shown and described.
